UNITED STATES PATENT OFFICE

FRANSISCUS C. J. DE BOTH, DECEASED, LATE OF NIMWEGEN, NETHERLANDS, BY
 JACOBUS J. D. DE BOTH, ADMINISTRATOR, OF NIMWEGEN, NETHERLANDS;
 JOHANNES PETRUS MATHEUS DE BOTH NOW ADMINISTRATOR OF SAID FRANSISCUS
 C. J. DE BOTH, DECEASED

APPARATUS FOR CUTTING ASPHALT SHEETS

Original application filed June 16, 1927, Serial No. 199,314. Patent No. 1,726,215. Divided and this
 application filed April 9, 1928. Serial No. 268,698.

The present invention is a division of an application for patent filed June 16th 1927, Serial #199,314, upon Method and apparatus for making and method of applying asphalt plates.

The present invention, in its broad aspect, has reference to improvements in cutting machines for forming asphaltic, bitumastic, asphaltic-granito, and the like, plates, for use as floor, aisle, wall or other surface coverings. Heretofore it has been customary in the art to lay asphaltic coverings in mass, and this has largely been due to the inherent nature of asphalt and bitumen which has rendered it impractical to lay the same in the form of plates. By nature asphalt and bitumen are spongy and inherently resilient, thus resisting efforts to produce plates of uniform size and thickness, and texture. The prior Patent #1,643,059 granted September 20th 1927, discloses how such plates may be produced practically, and the present invention points out how the asphalting sheet (as defined in the co-pending application filed April 9th 1928, Serial #268,696) may be cut up into such plates.

More particularly it is the purpose to provide a novel cutting device wherein means are provided for discharging the plate after it has been cut, and wherein means are provided for positively controlling the action of the cutter to the end that plates may be cut from a sheet of asphalt stock quickly, cleanly, and economically, and of uniform size and thickness. To this end is provided a cutter, and spring pressed means in conjunction therewith for pressing upon that portion of the surface of the stock which will form the plate, when cut, thus preventing "roaching" of the plate, and enabling the cutter to define clean edges. The presser also serves as a discharge means for cleaning or removing the plate from the blade, and the means of attaching the cutter head to the machine is concealed back of the presser so that it will not gum-up and be hard to replace or remove. The cutting apparatus, considered in its assembled form, is simple in construction, positive in operation, and may be set up and

operated without greatly modifying ordinary shop practices.

In the drawing wherein is illustrated the preferred embodiment of the invention:

Figure 1 is an assembly view of my cutting apparatus,

Figure 2 is a sectional detail of my cutting head, and

Figure 3 is a bottom plan view of the cutter head.

In the drawing wherein like characters of reference are used to designate like or similar parts throughout the several views.

The cutting machine has a base (1), a platform (2), and standards (3) carrying across and journaled in their upper ends a shaft (4). One standard rises above the other standard to form a supporting extension (5). The shaft (4) is slidably mounted in the standards (3) and has keyed thereon spaced discs (6) which are adapted to alternately and frictionally engage the periphery of a driven disc (7) when the shaft is moved by lever connections (8) to control handle (9). The control handle (9) is mounted on the platform (2). Thus by manipulation of the control handle (9) the spaced discs (6) are moved to either the neutral position, shown in Figure 1, or to drive or reverse the disc (7). Disc (7) is mounted on the upper end of a vertical screw (10) carried by the frame (11) and on the lower end thereof is attached, as by a bolt (12), the cutting head (13). The cutting head has a square (or other shaped) base plate (14) bossed as at (15) and recessed as at (16) to receive the head of screw or bolt (12), and is peripherally flanged as at (17). Bolted as at (18) to the flanged portion (17) of the base plate (14) are knives (19), and the same bolts (18) retain inverted L-shaped brackets (20) having openings in their overhanging portions to receive pins (21). The pins (21) extend through the base plate (14) and carry a presser plate (22) which works in the space between the blades, and is normally pressed down by springs (23) about the pins (21) and pressing against stop collars (24) on the pins and against the brackets (20) to force the pins down. The presser plate (22)

also serves to clean the blades or knives (19) and to remove the objects cut thereby from the blades or knives, and it also serves to protect and keep clean the bolt (12) which lies in the space behind the presser plate. When the handle is thrown to feed down the screw or worm (10) the cutter head is moved toward and through the object to be cut, and reverse movement of the screw will withdraw 10 the cutter head. The ear (25) facilitates handling the presser plate; and a suitable drum or pulley (26) is mounted on the shaft (4) to actuate the same from a power plant (not shown).

15 It is obvious that those skilled in the art may vary the details of construction as well as the arrangements of the parts without departing from the spirit of the invention, and therefore it is not desired to be limited 20 to the foregoing disclosure except as may be required by the claims.

What is claimed is:—

1. In a cutting machine, a cutter head having a base plate formed with upwardly extending peripheral flanges, knives engaging the flanges and extending down past the under face of the base plate, a plurality of L-shaped brackets on the flanges and each disposed with one arm extending inwardly 25 above the upper face of the base plate, means extending through the flanges and the knives and brackets for holding the latter on the flanges, a presser and cleaning plate mounted between the knives below the base plate, pins 30 extending through the base plate and upwardly through the inwardly extending arms of the brackets and supporting the presser plate, and springs about the pins above the base plate and engaging the arms of the 35 brackets to normally urge the presser plate 40 away from the base plate.

2. In a cutting machine, a cutter head having a rectangular base plate formed with a continuous upwardly extending peripheral 45 flange about its edges, knives carried by the flange and extending down past the under face of the base plate, a plurality of inverted L-shaped brackets on the flanges and each disposed with one arm extending inwardly 50 above and substantially parallel to the upper face of the base plate, securing means extending through the flanges and the knives and brackets for holding the knives and brackets on the flange, a rectangular 55 presser and cleaning plate of substantially the same size as the base plate mounted between the knives below the base plate, a plurality of pins extending through the base plate and upwardly through the inwardly 60 extending arms of the brackets and supporting the presser plate, and springs about each of the pins above the base plate and engaging the under side of the arms of the brackets to normally urge the presser plate away from 65 the base plate.

3. In a cutting machine, a cutter head having a base plate, a plurality of knives carried at the edges of the base plate and extending downwardly past the under face of the base plate, supporting means for the knives 70 formed on the base plate and extending above the upper face thereof, a plurality of angularly shaped brackets each disposed with an arm extending inwardly and substantially parallel with the upper face of the base plate, 75 securing means extending through the knives, the supporting means for the knives, and the brackets for holding the knives and brackets on the supporting means, a presser and cleaning plate below the base plate and of a size 80 to fit and move freely in an upwardly and downwardly direction between the knives, a plurality of pins carried by the presser and cleaning plate, and extending upwardly through the base plate and through the inwardly extending arms of the brackets, and each pin carrying a coil spring on its end 85 above the base plate and abutting the under side of the inwardly extending arms of the brackets to normally urge the presser and 90 cleaning plate away from the base plate.

In testimony whereof, I affix my signature hereunto.

JACOBUS J. D. DE BOTH,
Administrator of the Estate of F. C. J. de Both, Deceased.
